CENTERING DEVICE

Herbert H. Smith, Cleveland, Ohio, assignor to
 National Malleable and Steel Castings Company, Cleveland, Ohio, a corporation of Ohio

Application July 11, 1944, Serial No. 544,428

10 Claims. (Cl. 213—21)

1

This invention relates to a centering device for car couplers.

The couplers for small railway cars, particularly those employed in mines, ordinarily must be capable of rotating laterally through a relatively wide angle. Such couplers tend to remain in an angular position when moved laterally for any cause unless means are provided to restore them to a central position. Centering devices have been heretofore proposed for this purpose, but many occupy considerable space on the under rigging of the car, a serious disadvantage in the installation of the devices on cars already equipped with relatively elaborate draft rigging equipment.

In accordance with this invention, a centering device for car couplers is wholly contained within the shank of the coupler. This arrangement is compact and does not interfere with the rigging already installed on cars. The centering device comprises a spring actuating plunger mounted within the shank of the coupler. The plunger has a plurality of laterally spaced bearings adapted for contact with corresponding laterally spaced surfaces on the attaching means for the coupler located on the car. Desirably, the coupler has a rearwardly bifurcated hollow shaft having a spring means in the shank which reacts in one direction against a spring abutment in the shank and in the other direction against a transversely extending surface on the connecting means on the car for connecting the coupler to the car. The connecting means on the car extends between the bifurcations of the shank. The spring means and laterally extending surfaces are so constructed and arranged as to provide a contact therebetween to produce an additional component of force to one side of the centerline of the coupler when the coupler is angled from the central position, tending to move the coupler to the central position.

The invention is applicable to couplers with or without resilient or cushioning means for shock absorption purposes. For example, the centering device of this invention may be incorporated in the shank of a coupler on a car which has no resilient means such as that which obtains on some locomotives in which the resilient means is associated with the coupler of a mine car. Again, as in the first specific embodiment of this invention illustrated, the centering device may be associated with the resilient means. In this embodiment the laterally spaced surfaces which contact the spring means are located on the front follower of the resilient means of the coupler. These spaced surfaces may, of course, be associated with different types of draft rigging utilizing resilient means. For example, the spaced surfaces may be associated with a yoke employed extensively for certain types of resilient means.

An object of this invention is to center the coupler of cars effectively and economically.

2

Another object of this invention is to render responsive substantially immediately the position of the couplers on a train of cars to angular changes in the track over which the car passes.

5 Another object of this invention is to position a coupler on a mine car or the like to a substantially central position when the coupler thereof is rotated for the emptying of the car.

10 A more comprehensive understanding of this invention is obtained by reference to the accompanying drawings, in which:

Figure 1 shows a horizontal section of the centering device of this invention, associated with a tail bolt on a draft rigging.

15 Figure 2 illustrates a vertical section of the centering device shown in Fig. 1 along the line 2—2 thereof.

Figure 3 is a partial horizontal section showing the angular movement of the centering device shown in Figs. 1 and 2 along the line 3—3 of Fig. 2.

20 Figures 4 and 5 illustrate a plane view and side view respectively of parts of the centering device shown in Figs. 1 and 2.

25 Figure 6 illustrates an end view of one of the parts shown in Figs. 4 and 5.

Figure 7 shows a horizontal section of a modification of the centering device illustrated in Figs. 1 to 6; and

30 Figure 8 shows a vertical section of the modification of the centering device shown in Fig. 7, along the line 8—8 thereof.

In the embodiment of the invention illustrated in Figs. 1 to 6, a coupler 10 has a rearwardly extending hollow shank 11 which is connected to a cushioning means located on the car. The cushioning means may be of any type and consist in the embodiment illustrated of front and rear followers 12 and 13, respectively, with appropriate lugs 14 for abutments to restrict the horizontal movement of the followers within predetermined limits. Between the front follower 12 and the rear follower 13 a helical spring 15 is extended, reacting in one direction against the front follower 12 and in the other direction against the rear follower 13. In juxtaposition of the front follower 12 is a coupler butt seat 16 which is adapted to receive the butt end of the coupler shank 11. A tail bolt 17 passes through the rear follower 13, the spring 15, front follower 12 and coupler butt seat 16, and serves as part of the connecting means for connecting the shank 11 of the coupler to the follower acting means.

The butt end of the hollow shank 11 is adapted 45 to angle within a predetermined arc in the butt seat 16 and is bifurcated so as to extend above and below the end of the tail bolt 17 adjacent butt seat 16. The shank 11 of the coupler is connected to the follower acting means or other 50 resilient means on the car by means of a vertical pin 18 which passes through each of the bifurcations of the shank and the tail bolt 17, afford- 55 ing a positive connection.

60

ing relatively angular movement between the shank and the follower acting means. In the hollow rearward end of the shank 11 a centering plunger 19 is actuated by a spring 20. The spring 20 reacts in one direction against an abutment 34 in the shank 11 and through it toward the head of the coupler 10. In the other direction the spring 20 reacts against the centering plunger 19. The centering plunger 19 is bifurcated and has at least two laterally spaced bearings 21, one of which is on each side of the vertical pin 18. At least two transversely laterally extending surfaces 22, one of which is on each side of the vertical pin 18, are located on the butt seat 16 or other means on the car for attaching the coupler to the car. Each of the laterally extending surfaces 22 is adapted to receive and to contact one of the laterally spaced bearings 21.

The construction of the spring actuated laterally spaced bearings 21 and laterally spaced surfaces 22 affords an extremely satisfactory means for centering the coupler on the car. When the coupler is angled from the central position the contact between one pair of the laterally spaced bearings 21 and its associated pair of the laterally spaced surfaces 22 produces an additional component of force to one side of the centerline of the coupler, tending to move the coupler to the central position. This is illustrated in Fig. 3, in which the shank 11 of the coupler is shown angled in a clockwise direction with respect to the car on which the coupler butt seat 16 and tail bolt 17 are located. This action increases the compression on the spring 20. The bearing 21 which is in contact with the surface 22, is actuated by the spring 20 through the centering plunger 19 to produce an additional component of force in a counter-clockwise direction tending to move the shank 11 and the coupler to the central position. The butt seat 16 is constructed so that it is capable of rotating 360° in relation to the front follower 12 when the car to which the follower 12 is attached is rotated in accordance with the practice of emptying cars in train. This construction is shown in Fig. 6 in which the coupler butt seat 16 may be rotated relative to the car. For example, the coupler together with the butt seat 16 remains stationary while the car with its associated follower acting means is rotated to any angle desired. In this manner, one or a plurality of cars in train may be rotated while the remaining cars are stationary. Sometimes it is desirable to provide means, for example, a recession 23 on the front follower and a corresponding projection 24 on the coupler butt seat, for locking the coupler in a vertical position when the coupler is in its normal position.

In Figs. 7 and 8 there is illustrated a modification of the device shown in Figs. 1 to 6. A spring means comprising a spring 25 and a centering plunger 26 is contained within a hollow bifurcated shank 27. The spring 25 reacts in one direction against an abutment 28 and in the other direction against the plunger 26. By means of a vertical pin 29 the shank 27 of the coupler is connected to a tail bolt 30, forming part of the resilient means for absorbing shock on the car. The tail bolt 30 is constructed so that the bifurcations of the shank 27 fit in recesses in the tail bolt. The plunger 26 desirably extends laterally on each side of the vertical pin 29. Each of the lateral extensions of the plunger 26 form bearings 31. Corresponding laterally spaced bearings 32 on the tail bolt 30 cooperate with the bearings 31

located on the lateral extensions of the plunger 26. The bearings 31 contact the laterally spaced bearings 32 to produce an additional component of force to one side of the centerline of the coupler when the coupler is angled from the central position tending to move the coupler to the central position in substantially the same manner as in the first embodiment illustrated.

In the two embodiments illustrated, the centering device of this invention has been attached to a resilient or shock absorbing means located on the car. The centering device, however, may be attached to the car by any connecting means located on the car which connecting means does not necessarily involve shock absorbing or resilient means. For example, the centering device of this invention may be connected by means of a vertical pin to any bolt fixably attached to the car which is an appropriate position. The attaching means located on the car in such cases have bearing surfaces similar to the surfaces 22 shown in the first embodiment and surfaces 32 shown in the second embodiment.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What is claimed is:

1. In a coupler including a hollow shank, means for attaching said shank to a car including a vertical pin passing through said shank and a tail bolt member, said tail bolt member being detachably secured to the car structure for rotation about the longitudinal axis of said member, seat means at the end of said tail bolt, and a centering device in said shank comprising a plunger mounted within said shank, said plunger having a plurality of transversely spaced bearings in contact with said seat means, spring means in said shank reacting against said shank and plunger for urging said plunger bearings against said seat means, and longitudinally extending guide means on said plunger disposed laterally of said spring means and adjacent a side wall of said shank and adapted to engage therewith to maintain said plunger in proper operating position during horizontal angling of the coupler.

2. A centering device for a coupler comprising a tail bolt adapted for operative connection to a car structure, seat means associated with the forward end of said tail bolt, a hollow coupler shank pivotally connected to the forward end of said tail bolt, a centering plunger entirely within the confines of said shank, said plunger bearing against said seat means at transversely spaced points thereon, spring means within said shank reacting against said plunger and against stop means in said shank to urge said plunger against said seat means at said spaced points, and longitudinally extending guide means on said plunger positioned laterally of said spring means and being adapted to engage the inner side of said shank to maintain said plunger in proper operating position when the coupler is angled in a horizontal direction.

3. In combination, a coupler having a hollow shank, means for mechanically connecting said coupler with a cushioning means on a car including a coupler butt seat for receiving the end of said shank, said seat having a central opening, a tail bolt member extending through said open-

ing in said seat and having its forward end received in said shank and being pivotally connected thereto, said member being detachably secured with respect to said cushioning means for rotation about the longitudinal axis of said member, a plunger, and a longitudinally extending spring within said shank reacting between said plunger and stop means in said shank, said plunger bearing against said coupler butt seat at points spaced transversely of said coupler shank, said plunger having longitudinally extending guide means positioned adjacent a side wall of said shank and being adapted to engage therewith to limit lateral movement of said plunger with respect to said shank during horizontal angling of the coupler.

4. In combination, a coupler including a hollow shank, a coupler butt seat engaging the end of said shank, said seat having a central opening, a tail bolt member extending into said opening and being pivotally connected to said shank, said tail bolt member being detachably secured to a car structure for rotation about the longitudinal axis of said member, a centering device contained entirely within said shank and comprising a spring actuated plunger adapted for engaging said coupler butt seat, and means for guiding the horizontal movement of said spring actuated plunger throughout substantially the entire length thereof, said centering device being so constructed and arranged as to remain in fixed relation to said shank during rotation of said coupler around its longitudinal axis.

5. A centering device for a pivotally connected coupler comprising a hollow coupler shank, an abutment in said shank extending laterally from one side and spaced from the opposite wall to form an opening therebetween, a substantially U-shaped plunger within the confines of said shank having an arm extending into said opening for guiding said plunger, laterally spaced bearing means positioned near the end of said shank, said plunger having laterally spaced bearing portions adapted to cooperate with said bearing means, and spring means between the arms of said plunger and reacting between said abutment and said plunger to urge said bearing portions into engagement with said bearing means.

6. A centering device for a pivotally connected coupler comprising a hollow coupler shank, an abutment in said shank extending laterally from one side and spaced from the opposite wall to form an opening therebetween, a plunger adapted for longitudinal movement in said shank, said plunger having a pair of spaced longitudinal arms joined at one end by a transverse arm, one of said longitudinal arms extending into said opening for guiding said plunger, laterally spaced bearing means positioned near the end of said shank, said plunger having laterally spaced bearing portions adapted to cooperate with said bearing means and spring means between said arms and reacting between said abutment and said plunger to urge said bearing portions into engagement with said bearing means.

7. In combination, a car coupler having a hollow shank, tailbolt means having an enlarged forward end portion, said means being pivotally connected to said shank, spring means associated with said tailbolt means for cushioning longitudinal movement of said coupler, a front follower engaging the forward end of said spring means, a seat member interposed between said follower and said enlarged end portion of said tailbolt

means, a plunger within the confines of said shank having a pair of laterally spaced bearing portions adapted for engagement with said seat member, spring means in said shank reacting against said plunger to urge said bearing portions into engagement with said seat member.

8. In combination, a coupler having a hollow shank, spring means for cushioning longitudinal movement of the coupler, follower means adjacent the forward end of said spring means, connecting means rotatably associated with respect to said spring means and follower means and pivotally joined to said coupler shank, a seat member engaging said follower and being rotatable with said connecting means, said member having laterally spaced bearing means, a plunger within said shank and movable longitudinally thereof, spaced bearing portions on said plunger adapted normally to engage said bearing means on said seat member, abutment means in said shank, and spring means reacting between said abutment means and said plunger to urge said bearing portions into engagement with said bearing means.

9. In combination, a rotatable coupler having a hollow shank, spring means for cushioning longitudinal movement of the coupler, a follower adjacent the forward end of said spring means, said follower having a recess in the forward side thereof, connecting means rotatably associated with respect to said follower and pivotally joined to said coupler shank, a seat member for the end of said shank adapted for rotation therewith, said member having a projection adapted to be received in said recess for normally maintaining said coupler in operative position, and centering means in said shank comprising a plunger having laterally spaced bearing portions adapted for engagement with said seat member, and spring means reacting against said shank and said plunger to urge said bearing portions into engagement with said seat member.

10. In combination, a car coupler having a hollow shank, tailbolt means pivotally connected to said shank and being resiliently mounted for movement in a longitudinal direction, said means being rotatable with respect to the car, a seat member associated with the forward end of said means and being rotatable therewith, a plunger within the confines of said shank having a pair of laterally spaced bearing portions in engagement with said seat member when said coupler is in central position, spring means in said shank reacting against said plunger to urge said bearing portions against said seat member, one or the other of said bearing portions being adapted to remain in contact with said seat member during horizontal angling of said coupler to either side of its central position.
